ATTYS

UNITED STATES PATENT OFFICE.

AARON O. DAYTON, OF WILLIAMSPORT, PENNSYLVANIA.

SEAL-LOCK.

SPECIFICATION forming part of Letters Patent No. 275,026, dated April 3, 1883.

Application filed December 6, 1882. (No model.)

To all whom it may concern:

Be it known that I, AARON OGDEN DAYTON, of Williamsport, county of Lycoming, and State of Pennsylvania, have invented certain new and useful Improvements in Door-Fasteners for Freight-Cars, of which improvements the following is a specification.

This invention relates to that class of door-fastenings which have been adopted on all railroads as the most effective for protecting loaded cars from being tampered with between one station and another, and in which a wire and seal take the place of lock and key; and it is the object of my improvement to reduce such a fastening to its simplest form in construction, while rendering it more effective in operation than any heretofore used or applied in connection with a sliding door.

The requirements of a fastening for railroad traffic are as follows: It must be adapted to use in connection with a sliding door; it must be simple and of strong construction; it must be self-securing, so that it will not be displaced by the jolting of the car in motion or by any of the jars and shocks attending the making up and movements of trains; it must be capable of being readily operated when the door is to be opened or closed, and it must be protected against being tampered with or displaced without detection when it is once secured by seal-wire fastening generally used on loaded cars.

The nearest approach to what has been indicated by experience as the best adapted to the requirements of railroad traffic is the primitive hasp slipping over a staple, with a pin passed through the staple to hold the hasp in place, the wire being then passed through the pin and hasp and the seal affixed. This device reached a form in which it was quite effective, except in two important particulars: first, it required the use of a pin, which involved the use of a chain to prevent the loss of a pin; second, it embodied no suitable means of affixing the seal-wire free from exposure to abrasion, and it was capable of being unfastened without disturbing the seal-wire, and so without detection.

It is the object of my improvement to obviate all necessity for pins and chains to perfect the hasp-and-staple fastening, so that it

may be fitted closely and hold the sliding door snugly in place, may be used with as well as without a lock and key, may be secured with a wire and seal or with the thin metal strip sometimes substituted for the wire and seal on through-cars, with special provisions for protecting the seal-wire from being cut or broken by the working of the hasp while the car is in motion, and to render it impossible to open the door when once sealed without cutting or breaking the wire.

In the accompanying drawings, which form part of this specification, Figure 1 is an elevation of my improved fastening complete and secured with a wire and seal. Fig. 2 is a plan. Fig. 3 is a side elevation, showing the hasp in section, and by dotted lines showing the movement of the hasp over the staple or catch-piece. Fig. 4 is a plan of the plate which receives the inner end of the stud-pin. Fig. 5 is a side elevation of the stud-pin in place, with the holding-plate in section. Figs. 6, 7, and 8 are views showing a modification of the fastening, as hereinafter explained.

A represent the stud or pin, having at its inner end a head, a , and adjacent recess a' , and at its outer end a bent neck, a^2 , and a head, a^3 , as shown.

B is a plate having a circular opening, b , which is large enough to permit the head a of the stud A to pass through the same, and a straight slot, b' , connecting with the opening b , which is small enough to prevent the return of the head when the plate has been moved into position behind the head in the manner well understood. The plate, when in its proper position to hold the stud, is itself held by means of screws, as shown, and by means of this hole the stud A, when in proper position, is securely held in the frame of the car-door, and projects from the outside thereof.

C represents the hasp, having in one end the re-enforced hole, and about its center and near the outer end the vertical rectangular slots c' c^2 , as shown.

c^3 represents a small projection upon the plate C, about midway between the slots c' c^2 , which is provided with a suitable hole through which to pass the wire or thin strip of the seal, hereinafter referred to. The stud is slipped through the hole c in the hasp, being secured

in place by the plate B, and the hasp is thus suspended by its inner end, and has a free shackling movement upon the neck of the stud.

5 D represents a catch-piece corresponding in position and purpose with the main staple of the ordinary hasp. This piece consists of a shank portion, d, with threaded end d', having a nut, as shown, and a head portion, d², with curved bearing-face d³ and recess or cut-away portion d⁴, as shown in Figs. 1 and 3. A hole, d⁵, in the head portion of D is provided to receive the bow of a padlock when it is desirable to use one. This piece D is bolted 10 through the frame-post of the car at the door-opening in the proper position to project through one or the other slots of the hasp, according to the position of the door. This is the best form in which I have practically embodied my invention.

The operation is as follows: The hasp having been secured upon the stud A and the catch-piece to the car at the proper points, the door may be closed and fastened, or fastened without being entirely closed, by swinging the hasp over the catch-piece, which fits into one of the slots. The length of the slot in the hasp-plate being less than the head portion of the head-piece in a vertical plane, 25 the hasp-plate cannot be passed to place by a simple swinging movement in a horizontal plane from its axial point, but must be lifted and tipped into such position that the vertical slot can pass behind the projection of the 30 catch-piece, as shown in dotted lines, Fig. 3, and then be swung down into the vertical position, as shown in section-lines, Fig. 3. When in this position it will be seen that the hasp cannot be removed from the slot in the catch-piece without first inclining the hasp outward, and then raising it upward so as to lift it over the head of the catch-piece, and these two movements cannot possibly occur at the same instant from any jarring or jolting or other 35 movement of the car. Consequently the hasp can only be removed by hand, and, when once fastened by the seal-wire, cannot be removed by hand until the wire is broken. The stud at the outer end of the hasp and the head-piece both being of such form that they cannot be tampered with without detection, the fastening is thus absolutely protected, and the wire is not subjected to any abrasion or danger of being cut by the movements of the 40 hasp.

The above-described operation of the hasp obviates all necessity for the use of a pin, as heretofore, and cures all the trouble previously had with pins and chains.

To seal the car, a wire or tin strip is passed 60 through the hole d⁵ in the head portion d², and through the hole in the projection c³, and secured by a seal in the manner well understood; or the bow of a padlock may be passed through the hole d⁵ in the catch-piece. 65

I have described and shown the hasp with two slots for different positions of the door; but of course I claim my improvement whether one or two slots are used.

In the modification of the construction 70 shown in Figs. 6, 7, and 8, E represents a hasp-plate having longitudinal openings e e'; and F is a curved catch-piece adapted to project through these slots, and provided with an opening, f, as shown.

G represents a facing-plate, in the upper 75 end of which is a hole to receive the seal wire or strip, the upper end of this plate being curved or inclined forward toward the catch-piece.

The operation of these parts, thus combined, is similar to that of corresponding parts before described. The seal wire or strip in this modification is carried through the curved catch-piece and the facing-plate, instead of 85 through the projecting piece c³ and the hole through the catch-piece, as in the case first described.

Having thus fully described my invention, what I claim as new, and desire to secure by 90 Letters Patent, is—

1. In combination with the stud A, having the bent end, a hasp-piece, substantially as described, shackled on the stud, so as to have a lifting and swinging movement thereon, and 95 a catch-piece having an upward extension, the combination being and operating for the purpose of preventing a direct vertical or horizontal displacement of the hasp-piece, substantially as described. 100

2. In combination with the hasp-piece, having a capacity for a lifting and swinging movement, substantially as described, the catch-piece D, with head exceeding in length the 105 length of the slot in the hasp-plate, as described.

3. The fastening described, consisting of the stud A, hasp-plate e, with slots e' e², and projection c³, with hole for seal-wire, and the catch-piece D, having the head d², with cut-away portion d⁴, and opening for seal-wire, as 110 described.

This specification signed and witnessed this 29th day of November, 1882.

AARON OGDEN DAYTON.
